(57) **CLAIM**

The ornamental design for a motorized camera slider, as shown and described.

DESCRIPTION

FIG. 1 is a front, right and top perspective view of a motorized camera slider, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is a partial enlarged view of an area labeled 10 in FIG. 1; and,

FIG. 11 is a partial enlarged view of an area labeled 11 in FIG. 2.

The dot-dash lines depict symbolic break lines. The areas between the break lines form no part of the claimed design. The dash lines in the drawings depict portions of the motorized camera slider that form no part of the claimed design. In addition, the short dash-long dash lines in FIGS. 1–2 and 9–11 depict the boundaries of the enlarged views that form no part of the claimed design.
